UNITED STATES PATENT OFFICE.

STEPHEN J. GUSCOTT, OF CHICAGO, ILLINOIS.

DEVICE FOR STACKING RAILROAD-RAILS, LUMBER, &c.

SPECIFICATION forming part of Letters Patent No. 275,763, dated April 10, 1883.

Application filed January 11, 1883. (No model.)

To all whom it may concern:

Be it known that I, STEPHEN J. GUSCOTT, a citizen of the United States of America, residing at Chicago, in the county of Cook and State of Illinois, have invented certain new and useful Improvements in Devices for Loading and Stacking Railroad-Rails, Lumber, &c., of which the following is a specification.

This invention relates to devices for piling railroad-rails or similar articles as they are delivered from the mill, and also to loading them from the pile onto cars or wagons; and it consists in certain combinations of shafts connected by fast and loose clutches, roller-carriers, adjustable skids, and hauling-ropes running over adjustable pulleys and fast and loose winding drums or spools, as will be herein-after more fully described, and pointed out in the claims.

20 In order to enable others skilled in the art to which my invention appertains to make and use the same, I will now proceed to describe its construction and operation, referring to the accompanying drawings, in which—

25 Figure 1 is a side view of the invention arranged for piling or stacking the rails. Fig. 2 is a similar view, arranged for transferring them from a stack to a car. Fig. 3 is a plan view of Fig. 2. Fig. 4 is a perspective view of the winding-drums and their shifting clutches. Fig. 5 is a similar view of one of the adjustable guide-pulleys. Fig. 6 is a view of one of the shaft-clutches; and Fig. 7, a side elevation, partly in section, of the tripping device used 30 in loading the rails.

In rolling-mills where railroad-rails and similar articles are formed the rails are usually carried off, by a series of rollers set in a frame or track, to any point desired, and then lifted 35 by a number of persons and piled up until wanted, when they are again lifted and loaded upon cars or wagons for hauling away. To perform this labor of stacking and loading by machinery, I use a bed, A, of any desired 40 length, provided with rollers A', upon which the rails are carried off. Each roller is supplied with a bevel-gear, a, meshing with a similar wheel, a', upon a shaft, A'', journaled in brackets a''' on the side of the bed A. This 45 shaft is divided into sections opposite the different points at which it is desired to stack or load the rails, and the sections are revolved

together by means of a shifting clutch, a⁵, upon one section, and a similar clutch-disk, a⁶, made fast upon the other, as will be understood by 55 reference to the drawings.

In rear of the bed A, at either end, are castings B, formed with vertical grooves, in which is arranged a standard, B', having its outer face formed with a series of cogs, b, with which 60 meshes a spur-wheel, b', upon a crank-shaft, b'', journaled in brackets b''' upon the box or casting B. The upper ends of the cogged standards B' are surmounted by a cross-arm, B², to one end of which, (next the bed A) is 65 hinged an arm, B³, in the under side of which is a longitudinal groove, c, which is deeper at its center than at either end, as seen in Fig. 7. The hinge-joint between the cross-arm B² and the arm B³ is on its upper side formed with a 70 shoulder, c', so that while the hinged arm is free to fall it can only rise to a position horizontal with the cross-head B². The hinged arms B³ rest upon and are supported by two curved arms, C C, secured to a rock-shaft, C', 75 running across the machine, supported by the adjustable cogged standards B', and provided on each end with a crank-arm, C², from the outer end of which depends a rod, C³, provided with suitable weights, C⁴. The ends of the 80 cross-heads B² opposite to the bed or carrier A are provided with pins c², upon which are placed bars or skids D of a length sufficient to reach to the pile upon which the rails are 85 placed. The outer ends of these skids or bars D rest upon the top layer of rails in the pile, and various lengths are required, according as the pile may be higher or lower than the carrier A and upper ends of the standards B'.

E E represent four uprights, two of which 90 are placed in front and at either end of the sectional carrier A, and two in a similar position in rear of the pile of rails. Each of these uprights is provided with a sliding frame, E', 95 provided with a set-screw, e, for securing it at any desired height upon the upright, and formed with an arm, e', upon which is placed a grooved pulley, e², surrounded by a small vertical frame, E², and held in position by a pin, e³, passing through the arm e', as seen by Fig. 5. 100 In the rear of the pile of rails are also arranged two uprights, F F, somewhat higher than the ones E E, and carrying near their upper ends a shaft, F', upon which are two loose drums or

spools, G G, each of which is formed with one clutch-face, g, adapted to engage with and be revolved by the clutches F², arranged to turn with and to slide back and forth upon the shaft F¹.

f f represent two forked shifting-levers engaging the sliding clutches F² at one end, and fulcrumed upon a cross-bar, F³, extending across the device between the two uprights F; and the outer ends of the levers f f are connected by rods f' f' to the opposite ends of a vertical lever, G', pivoted upon the center of the cross-bar F³. One end of this last lever, G', is also provided with a shifting-rod, g', extending to a convenient position at one side of the frame.

In operation as many of these sections or devices are used as may be deemed necessary, and the shafts A² and F¹ are operated by power from the mill. The rails, as they leave the mill, are carried out by the rollers A' to the place at which they are to be piled up, where they are stopped. Each winding-drum G G is provided with a rope or wire cable, which is passed through under the grooved pulleys upon the uprights in rear of the stack or pile and carried forward to the carrier, where the rails are delivered. The ropes are each provided with a two-pronged fork, which is slipped upon the rail between the flange and head, as shown, and the clutches F² being thrown into gear with the drums or spools, the cord or rope is wound up, hauling the rail over the arm B³, cross-head B², and skid-bars D to any desired position upon the pile, when the drums are again thrown out of gear and the ropes carried back for another rail. It is evident that two or more rails may be handled at once, if desired, and they are easily and rapidly hauled into place, no matter how high or low the pile may be.

When it is desired to load the rails from the pile upon a car or wagon the latter is drawn up opposite the carrier A, the hauling-ropes are unrove from the pulleys just mentioned, and rove over those upon the uprights at the front of the machine and carried back to the stack, where they are secured to one or more rails, as before described. In addition to the skids D, reaching from the cogged standards to the stack, two other skids, D', are placed in position upon the pins c', reaching over the carrier to the car, and the cogged standards are raised by means of the spur-wheel and its crank to any desired height, where they are held either by a pawl or by a pin passed through the standards. The weights upon the pendent rods C³ are a little more than enough to balance the weight of the rail or rails to be moved, and when the drums are started these rails are hauled over the skids D to the arms B³. The attendant then lifts upon the weighted rods C³, and the hinged arms B³ fall, allowing the rails to slide down the skids D' to the car or wagon.

It is evident that but little attendance is needed to operate this device, and the rails

can be handled much quicker and easier than by the old mode. The same device is also applicable to the stacking and loading of lumber or any heavy object of a similar form, and one of the sections may be used for stacking while another is used for loading.

Having thus fully described my invention, what I claim as new, and desire to secure by Letters Patent, is—

1. In a device for stacking railroad-rails, lumber, &c., a carrier for bringing the rails from the mill, in combination with a shaft provided with shifting clutches, and loose winding-drums having ropes secured to them, adapted to haul the rails from the carrier to the pile, substantially as shown and described.

2. The combination, in a machine for stacking railroad-rails and similar articles, of a carrier, skids, or ways over which the rails are slid, and means for hauling them from the carrier to the stack or pile, substantially as described and shown.

3. In a device for loading railroad-rails or lumber, &c., the combination, with the vertically-adjustable standards provided with two sets of skids or ways, one reaching from the pile or stack to the standards and the other to the car or wagon, with means for hauling the rails, &c., from the stack over the ways to the car, substantially as shown and described.

4. In a device for stacking or loading railroad-rails, &c., a carrier provided with a series of rollers, each having a bevel-gear on one end, in combination with a shaft formed in sections clutched together, and provided with bevel-gears for operating the carrier, substantially as described and shown.

5. In a device for stacking and loading railroad-rails, &c., the combination of the vertically-adjustable standards B', having a cross-head, B², and hinged arm B³, with the supporting-arms C, secured upon a shaft and provided with weighted arms C², substantially as shown and described.

6. In a device for stacking and loading railroad-rails, &c., the standards B', provided with a hinged arm, B³, supported by the arm C of a rock-shaft, C', adapted to be tripped, as desired, and the skids or ways D D', in combination with the winding-drums G, provided with hauling-ropes, and the uprights E, having adjustable guide-pulleys, substantially as described and shown.

7. In a device for stacking and loading railroad-rails, &c., the shaft F', having shifting clutches F² and winding drums or spools G, in combination with the shifting-levers f f, fulcrumed upon the main frame, connecting-rod f' f', lever G', and shifting-rod g', substantially as and for the purpose set forth.

8. The frame or band E', formed with an arm, e', and provided with a set-screw, e, in combination with the grooved pulley e², frame E², adapted to pass over the arm e' and clasp the band E', and the pin e³, all constructed and arranged to operate substantially as and for the purpose set forth.

9. A device for stacking and loading railroad-rails, lumber, or similar objects, consisting essentially of a series of rollers forming a carrier, operated by a sectional shaft clutched together, by which any number of rollers in the carrier may be operated or allowed to lie idle, adjustable standards carrying the ends of skids or ways reaching to the stack or to the load, uprights at each corner of the device, provided with adjustable guide-pulleys, and a shaft at one end of the device, provided with loose winding drums and ropes, shifting clutches, and means for engaging or disengaging the clutches and drums at will, all combined and arranged to operate substantially 15 as and for the purpose set forth.
- In testimony whereof I affix my signature in presence of two witnesses.
